DESIGN FOR A DISPLAY CALENDAR

Martin E. Trolle, St. Paul, Minn., assignor to
Brown & Bigelow, St. Paul, Minn., a corpora-
tion of Minnesota

Application January 2, 1941, Serial No. 97,777

Term of patent 14 years

To all whom it may concern:

Be it known that I, Martin E. Trolle, a citizen of the United States, residing at St. Paul, county of Ramsey, and State of Minnesota, have invented a new, original, and ornamental Design for Display Calendars, of which the following is a specification, reference being had to the accompanying drawing forming part thereof.

Figure 1 is a front view of a display calendar, showing my new design.

Figure 2 is a side elevational view.

Figure 3 is a section on the line 3—3 of Figure 1.

The numerals and printed matter shown on Figure 1, are merely representative.

The characteristic feature of the design resides in the bars of translucent or transparent material of a color contrasting with the background of the display, extending through the display.

I claim:

The ornamental design for a display calendar, as shown and described.

MARTIN E. TROLLEN.
